Attorney

UNITED STATES PATENT OFFICE.

BERTHA A. UTTZ, OF FORT WORTH, TEXAS, ASSIGNOR TO W. A. UTTZ, OF FORT WORTH, TEXAS.

SASH LOCK.

Application filed January 24, 1922. Serial No. 531,338.

To all whom it may concern:

Be it known that I, BERTHA A. UTTZ, a citizen of the United States, residing at Fort Worth, in the county of Tarrant and State of Texas, have invented certain new and useful Improvements in Sash Locks, of which the following is a specification.

My invention relates to improvements in sash locks; and the object is to provide a simple device for locking the upper and lower sash members, or either of them, in any position desired for ventilation and circulation of air and at the same time for preventing burglars or other persons of evil intent from entering a house through the window. Another object is to provide a device which is detachable and adjustable, the device not being attached at all to the window frame. Another object is to provide a simple device in compact form which can be carried in a suit case or hand bag for use on the windows of a hotel or other establishment so that a person can protect himself at night. Other objects and advantages will be fully explained in the following description and the invention will be more particularly pointed out in the claims.

Reference is had to the accompanying drawings which form a part of this application.

Fig. 1 is a broken sectional view of window sash and the frame thereon which is shown in side elevation the improved lock. Fig. 2 is a plan view of the lock. Fig. 3 is a side elevation of the same. Fig. 4 is a plan view of the locking member of the upper sash. Fig. 5 is a plan view of the locking member for the lower sash. Fig. 6 is a side elevation of the locking devices, being a view of the left side of the devices, as shown in Fig. 3.

Similar characters of reference are used to indicate the same parts throughout the several views.

The drawings show a frame 1 of a window and the upper sash member 2 and a part of the lower sash member 3. The locking members 4 and 5 are mounted on a carrier 6 which has on one side a right angled flange 7 which rests against a part 8 of the window frame, and on the other side a spring 9 which is attached to a lug 10 on the carrier 6 and bears against a stop 11. The carrier 6 can be positioned at any required height in the window frame because the

spring 9 will make friction enough to hold the carrier wherever wanted. The spring 9 also makes the carrier 6 adjustable for different widths or thicknesses of sash, that is, the carrier 6 will be supported between the portion 8 of the window frame and the stop 11 although the space may be wider or narrower between the window frame member and the stop 11.

The lock for the lower sash consists of a blade member 5 and a shank member 12 which is slidably mounted in a keeper or loop 13 which may be formed integral with the carrier 6 or which may be brazed or soldered thereto. A plunger 14 is slidably mounted in a keeper 15 which may be formed integral with the carrier 6. The plunger 14 has a beveled head 16 for holding the shank 12 at different adjustments. The lower sash will be raised until it strikes the lower end of the plunger 14, but cannot be raised higher because the teeth on the blade member 5 will engage the stop 11. The plunger 14 has a foot flange or lug 17 against which the lower sash will stop. The lock for the lower sash consisting of the toothed blade 5 and the shank 12 may be made integral. A stop 24 on carrier 6 prevents displacement of the lock member 5.

The lock for the upper sash consists of a pivoted bar 4 having a toothed blade 18 for engaging the frame of sash 2. The bar 4 is pivoted on the lug 19 which projects from the carrier 6. The bar 4 is manually operated to bring it in position for engaging the sash 2. The bar 4 carries a supplemental toothed blade 20 integral therewith. If the blade 18 does not stop the sash, the bar 4 will be pushed endwise, the slot 21 permitting the endwise motion, so that the blade 20 will engage the frame 8. The sash 2 will thus be doubly locked. An opening is made in the flange 7 for the passage of the blade 20. The flange 7 and the spring 9 have handles 22 for convenience in inserting the locking device in between the frame member 8 and the stop 11. The position of the sash cord 23 is shown in Figs. 1 and 2. The locking member 4 is provided with a handle 25 for convenience in positioning this member. Various changes in the construction of the several parts may be made without departing from my invention. It is apparent that this device may be inverted and

used for the same purpose and particularly in case of a broken sash cord.

What I claim, is,—

1. A sash lock comprising a carrier movable to any part of a window frame, a locking member for the lower sash slidably mounted on said carrier, a plunger to be actuated by the lower sash for causing said lock to engage a stop on the window frame, and means carried by the lower sash for actuating said plunger.
2. A sash lock comprising a carrier movable to any part of a window frame and a spring for holding said carrier in position after the carrier is located, a locking member for the lower sash slidably mounted on said carrier, and a plunger provided with a foot piece to be actuated by the lower sash to cause said locking member to engage a stop on the window frame.
3. A sash lock comprising a carrier movable to any part of a window frame and a spring for holding said carrier in position after the carrier is located and a locking

member pivotally connected to said carrier 25 and provided with a locking blade adapted to engage the upper sash when the locking member is swung into operative position and provided with a supplemental blade for engaging the window frame.

4. A sash lock comprising a carrier movable to any part of a window frame and a spring for holding the carrier in place after it has been located, a locking member for the lower sash slidably mounted on the carrier and slidable means mounted on the carrier to be engaged by the sash for causing said locking member to engage a stop on the window frame, and a locking member for the upper sash pivotally mounted on said 40 carrier and provided with one blade for engaging the upper sash and provided with a supplemental blade for engaging the window frame.

In testimony whereof, I set my hand, this 19th day of January, 1922.

BERTHA A. UTTZ.
